United States Patent

Des. 236,853
Patented Sept. 16, 1975

236,853

DOCUMENT SORTER

Louis J. H. Lucker, Tegelen, and Theo P. C. Breuers,
Venlo, Netherlands, assignors to Oce-van der Grinten
N.V., Venlo, Netherlands

Filed Aug. 1, 1974, Ser. No. 494,352

Term of patent 14 years

Int. Cl. D18—99

U.S. Cl. D64—11 R

FIG. 1

FIG. 2

FIG. 3

FIG. 4

FIG. 5

FIG. 6

FIG. 7

FIG. 8

FIG. 1 is a front elevational view of a document sorter showing our new design;

FIG. 2 is a rear elevational view thereof;

FIG. 3 is a right side elevational view thereof;

FIG. 4 is a left side elevational view thereof;

FIG. 5 is a view thereof taken along line 5—5 in FIG. 1;

FIG. 6 is a top plan view thereof;

FIG. 7 is a bottom plan view thereof; and

FIG. 8 is a view thereof taken along line 8—8 in FIG. 1.

We claim:

The ornamental design for a document sorter, substantially as shown and described.
